TRIMMING APPARATUS

John C. Smith, Norwalk, Conn., assignor to Hat Corporation of America, Norwalk, Conn., a corporation of Delaware

Application May 15, 1936, Serial No. 79,915

14 Claims. (Cl. 223—16)

This invention relates to apparatus for trimming material and especially to apparatus for trimming the brim portion of a hat.

In the manufacture of hats, and particularly hats made of fur, felt, fabric, and the like, after the hat has been given a preliminary shape it is placed upon a special shaping block and is there given its final form. In shaping and finishing a hat, the outer portion of the brim, constituting the scrap material, is usually passed downwardly and inwardly from the outer edge of the brim shaping portion to a reduced section of the block and a string or the like drawn to encircle the scrap, thus tautly securing the hat on the shaping block. This tightly drawn string causes a portion of the scrap material to be disposed at an angle to the regular brim portion of the hat.

The operations usually performed on the hat while positioned on the special shaping block, above mentioned, consist of ironing, pouncing and luring. These operations are usually performed by a machine in a first treatment and then by hand in a second treatment. Following the hat shaping steps just described, the string is removed, the hat is taken from the block, and then the hat brim is trimmed to the desired width and contour relative to the crown.

Most of the trimming machines heretofore provided for trimming hat brims were adapted to perform this function only with hats having flat or substantially flat brims or hats wherein the edge of the brim was equidistant from the crown throughout its entire periphery. Also, most of these brim trimming machines proposed in the past had complicated automatically driven apparatus for moving the hat relative to the cutter. Accordingly most of the previous efforts resulted in complicated costly machines having a very limited field of use.

It is a primary object of the present invention to provide a very simple and inexpensive trimming apparatus, especially adapted to trim hat brims having a wide variety of uniform and non-uniform shapes.

Also, heretofore in some of the forms of trimming apparatus for hat brims it was necessary to provide special templet apparatus for guiding and directing the trimmers or cutters with respect to the brim in order that the brim might be given the desired shape. In many of such trimming machines it was necessary to provide a separate or new templet each time a new or different brim shape was desired. This, of course, necessitated the inconvenience of disassembling and reassembling a portion of the machine, delayed

production, and increased production cost. In the absence of a special templet apparatus the trimming machines heretofore proposed were generally incapable of trimming the brim to a uniform width. 5

In many cases, especially in women's hats, it is desirable that the brim be of varying widths relative to the crown at different points so that various style effects may be obtained. Also, with some forms of hats it is desirable to have the various sections of the brim at various angles and in divers shapes or forms relative to the crown. All of these special shapes represent special problems with the machines heretofore provided for trimming brims. In many such instances it was necessary to resort to manual trimming with a pair of hand shears. 10

It is an important object of the present invention to provide a trimming apparatus which will trim even very irregular shaped brims, thereby dispensing with slow, costly, and nonuniform hand trimming operations now used. 20

It is a further important object of the present invention to provide a trimming device with which, in the trimming of brims to varying contours, there is eliminated the necessity of providing a special templet apparatus, or any complicated automatic mechanism for shifting the hat relative to cutters. 25

To this end there is provided, as an important feature of the invention, means associated with the cutters, which are cooperable with the angularly disposed portions of the brim for automatically guiding the material relative to the cutters or trimmers. In its preferred form a portion of the 30 guiding means is formed by the cutter itself. 35

Another object of the invention is the provision of a material feeding device associated with the cutters which automatically compensates for varying thicknesses in the material so as not to crush and damage the same, or to mar the outer appearance thereof. 40

In accomplishing this desired object there is provided, as a further feature of the invention, a pair of semi-floating feed rollers which are positioned at either side of one of the cutting elements, and which are movable relative thereto, according to variations in the thickness of the material being trimmed so that at all times the same amount of feeding pressure is applied to 45 the hat. 50

Still another feature of the invention resides in the provision of a trimming device for trimming material having angularly disposed and/or irregularly shaped brim portions, in which there is 55

included a rotary cutter having positioned at opposite sides thereof semi-floating rollers with oppositely bevelled peripheral faces defining an annular groove, and in which there is also included 5 a second rotary cutter which is cooperable with the first mentioned cutter and has positioned at one side thereof a roller, the roller and the second rotary cutter having oppositely bevelled peripheral faces complementary to the oppositely bevelled peripheral faces of the first described 10 rollers and extending into the annular groove defined thereby to cooperate with the peripheral faces of the first mentioned rollers and with the angularly disposed portions of the material for guiding and/or feeding the material 15 relative to the cutters.

Yet another feature of the invention resides in the provision of a special guide means associated with the cutters and rollers hereinbefore mentioned 20 which is adapted to cooperate with the angularly disposed portions of the material to guide and direct the material to the cutters and associated rollers. This structure is such that the hat may be fed automatically through the machine 25 at a fast rate or may be slowed down any extent or even stopped by merely pressing one's fingers onto the hat and underlying special guide means.

Other and more specific features residing in 30 advantageous forms, combinations and relations of parts will hereinafter appear:

In the drawings:

Figure 1 is a side view of the device embodying the invention, the stationary guide being omitted 35 in order to more clearly illustrate the cutters and associated rollers.

Fig. 2 is a front view of the device showing the manner in which a hat is directed and fed relative to the cutters, a portion of the hat brim being broken away in order to more clearly illustrate certain of the parts of the device.

Fig. 3 is a fragmentary detail view showing the cutters and associated rollers and the stationary guide member.

Fig. 4 is a detail sectional view taken on the line 4—4 of Fig. 3.

Fig. 5 is a view showing the hat positioned on the shaping block.

Fig. 6 is a detail view showing the manner in 50 which the stationary guide member cooperates with the angularly disposed portions of the hat brim to assist in guiding and directing the brim relative to the cutters and associated rollers.

Referring more particularly to the drawings, 55 there is shown a base 10 on which there is mounted and secured thereto in any suitable manner a frame 11. Preferably, and as illustrated, the frame is secured to the base by means of a plurality of bolts 12 which pass through suitable 60 holes in cooperating flanges 13 and 14 formed respectively on the base 10 and the supporting frame 11 and which are held in place by nuts 15. If preferred, the base and frame may be made integral or the frame secured directly to a 65 bench table, or the like, if the cutter section of the apparatus projects beyond the edge thereof.

Carried by the frame 11 is an upper shaft 16 supported in front and rear bearings 17 and 18 in the yoke portion 19 constituting the upper 70 arm 20 of the frame. Also carried by the frame is a lower shaft 21 supported in front and rear bearings 22 and 23 in the yoke portion 19a constituting the lower arm 24 of the frame, the upper and lower arms of the frame being connected by an intermediate supporting arm 25

which, as shown, may be formed integral therewith.

Concurrent rotation of the shafts 16 and 21 in the present preferred form of the apparatus is achieved by providing cooperating gears 34 and 35 respectively fixed to portions 36 and 37 of the shafts which extend rearwardly from the supporting frame by screws 29 and 33 passing through the hub portions 27 and 31 of the respective gears. Longitudinal movement of the upper shaft 16 is prevented by a collar 26 suitably secured to the shaft by a set screw 28 and by the hub portion 27 of the gear 34 positioned respectively at opposite sides of the bearing 18. Longitudinal movement of the lower shaft is similarly prevented by a collar 31 suitably secured to the shaft by a set screw 32 and by the hub portion 31 of the gear 35 positioned respectively at opposite sides of the bearing 23. A pulley 38 secured to the lower shaft with a screw 39 affords a convenient means by which the shafts may be connected to any suitable prime mover by a belt or the like.

Carried by and rotatable with portions of the shafts 16 and 21 which extend forwardly from the front bearings 17 and 22 are a pair of cooperating rotary cutters 40 and 41 which may be as shown, conveniently fixed thereto by pin connections 42 and 43 (see Fig. 4). As an aid in preventing movement of the cutters longitudinally of the respective shafts, the upper shaft is provided with a shoulder 44 against which the cutter 40 is held by the pin connection 42 and by the sleeve collar 46a which is held against the cutter 40 by the nut 47a associated with the threaded outer portion 48a of the upper shaft; and, the lower shaft is provided with a shoulder 45 between which and the cutter 41 there is interposed a sleeve collar 46 against which the cutter 41 is held by the pin connection 43 and the nut 47 which is associated with the threaded outer portion 48 of the lower shaft and is engageable with the cutter to urge it in the direction of the shoulder.

Of particular importance, according to the present invention, positioned at opposite sides of the upper cutter 40 is a pair of rollers 49 and 50 having angularly disposed peripheral faces 51 and 52 defining an annular groove 53 in which projects the material cutting portion 40' of the cutter 40. Preferably these rollers are carried by the shaft 16 on which the cutter 40 is fixed.

Movement of the rollers transverse the carrying shaft is permitted by providing the rollers 49 and 50 with shaft encircling bores 54 and 55 which are of greater diameter than the portions of the shaft with which they are associated. Movement of the rollers 49 and 50 longitudinally of the shaft is prevented by collars 56 and 57 which are secured to the shaft by the set screws 56' and 57' respectively and by the cutter 40. There are thus provided rollers which are in semi-floating relation with respect to the cutter and to the shaft.

Positioned at one side of the lower cutter 41 is an associated lower roller 58, which may be and preferably is, as shown, carried by the shaft 21 on which the lower cutter 41 is fixed and held from relative movement therewith by the set screw 58' which is adapted to pass through the hub portion 59 of the roller and engage the shaft.

The peripheral faces 60 and 61 respectively of the lower cutter 41 and associated roller 58 are angularly disposed and extend into the annular groove 53 defined by the complementary angular-

ly disposed peripheral faces 51 and 52 of the rollers 49 and 50 carried by the upper shaft 16 to cooperate therewith in the guiding and feeding the material to be trimmed.

5 To accommodate the material cutting portion 40' of the upper cutter and permit a proper positioning thereof relative to the material cutting portion 41' of the lower cutter 41, the lower roller 58 is spaced a slight distance from the lower cutter and is formed with a slight peripheral chamfer 62.

10 In the operation of the device the material to be trimmed is maintained in association with the material cutting portions 40' and 41' of the cutters by the cooperation of the semi-floating rollers 49 and 50 which rest upon the material, and by the angularly disposed peripheral faces 60 and 61 of the lower cutter and associated roller over which the material is passed.

15 20 With this construction, the pressure upon the material passing through the device is always uniform, because whether the particular piece of material passing therethrough varies in thickness or whether different pieces of material having different thickness are passed therethrough the semi-floating rollers will automatically compensate therefore.

25 The feeding of the material is accomplished by the lower roller and cutter 58 and 41 which are fixed to the shaft 21 and against the angularly disposed peripheral faces 60 and 61 of which, as above explained, the material is held with a uniform pressure by the floating rollers 49 and 50.

30 35 A particularly advantageous application of the invention is the trimming of material which has been, prior to the trimming operation, folded or formed in such a way that the crease defines a line which is the same as or is equidistant from the line along which it is desired to cut or trim the material. In trimming such a material, the angularly disposed portions are positioned in the device between the complementary angularly disposed peripheral faces 51 and 52 of the semi-floating rollers 49 and 50 and faces 60 and 61 of the lower cutter 41 and associated roller 58. In this manner the material is held in a definite position relative to the material cutting portions 40' and 41' of the cutters and is trimmed on the line defined by the crease or on a line equidistant from the crease depending upon the particular adjustment of the device.

40 45 50 In Fig. 5 there is shown a hat 66 positioned on a shaping block 67 in the usual manner, with an outer brim 68, constituting the scrap, being angularly disposed relative to a regular brim 69, to shape a deformation 70 and the line of meeting of angularly disposed portions 71 and 72 defining the line along which it is desired to trim the brim. The string 73 which encircles the outer brim or scrap is for the purpose of drawing the brim taut on the block during certain of the finishing operations and to clearly define the line of demarcation between the regular brim and the scrap. The dash line 74 is merely to show the crown portion of a hat of a style different than the one illustrated in full lines.

55 60 65 The apparatus of the present invention is especially adapted for the trimming of the scrap from the brim of a hat shaped for example as illustrated in Fig. 5, in a manner now briefly described.

70 75 In the trimming of the brim 69, after the string 73 is removed and the hat 66 taken from the shaping block 67 the scrap portion 68 is fed and

guided to the device by hand until the angularly disposed portions 71 and 72 of the brim are properly positioned between the complementary angularly disposed peripheral portions 51 and 52 of the semi-floating rollers 49 and 50 and faces 60 and 61 of the lower cutter 41 and associated roller 58 until the deformation or edge 70 is aligned with the material cutting portions 40' and 41'.

75 80 85 In this position the semi-floating rollers 49 and 50, due to their weight, press downwardly 10 upon the angularly disposed portions 71 and 72 respectively of the brim to cooperate therewith and with the angularly disposed peripheral portions 60 and 61 of the lower cutter 41 and associated roller 58 to guide and to feed the brim relative to the material cutting portions 40' and 41' of the cutters 40 and 41 respectively in such a way that the line of cut is coincident with the deformation 70 or line of demarcation between the angularly disposed brim portions 71 and 72. 20

90 95 After the brim has been thus properly positioned relative to the cutters, the angularly disposed peripheral faces 51, 52, 60 and 61 guide the work, relative to the cutters 40 and 41, and further exact guiding by the operator is, therefore, 15 unnecessary. Also the semi-floating rollers 49 and 50 press the hat onto the faces 60 and 61 of the cutter 41 and roller 58 with sufficient force to cause the latter to feed the work. Regardless of variations in the thickness of the material the 20 semi-floating rollers impart the exact same weight on the work; consequently there is no danger of crushing the material or marring its appearance.

100 105 110 It will be appreciated that the guide formed by the faces 51, 52, 60, and 61 is equally effective for hats wherein the deformation 70 may be close or distant from a crown 66', or both close and distant in the one hat, and also for hats wherein the brim may be disposed at a right angle, at an acute angle, or at various angles relative to the crown. 40

115 120 125 The adaptability of the device to variations in the thickness of a given piece of material as well as in the thickness of different pieces of material, as heretofore explained, is of particular importance in the trimming of hat brims. In the absence of this feature and in apparatus with fixedly spaced or spring pressed rollers variations in thickness of the brim would cause variations in the pressure on the brim and would produce uneven spots on the brim, thus negating to a considerable extent the prior finishing operations to which the hat had been subjected.

130 135 140 As an aid in directing the brim to the cutters 40 and 41 and associated rollers and as a further feature of the invention, there may be provided a stationary guide 76. A bracket 80 with which the guide is associated by means of a bolt and slot connection 79 may be, as shown, conveniently fixed to the frame by means of one of the bolts 12 with which the frame is secured to the base 10 to thereby support and maintain the guide in proper relation with the cutters 40 and 41 and associated rollers. 65

145 150 155 The guide, which is shown in detail in Fig. 3, has a substantially arcuate portion 81 which extends toward the cutters 40 and 41 and in line therewith. The arcuate portion is provided with angularly disposed or bevelled upper side walls 70 82 and 83 which are adapted, as shown in Figs. 2 and 6, to partially support the hat and to cooperate with the angularly disposed portions 71 and 72 of the brim to guide the same to the cutters and rollers. Vertical adjustment of the 75

guide is accomplished by means of the bolt and slot connection 79 between the guide and the supporting lug 80. The use of this guide 78 facilitates the cutting operation and insures a straight travel of the edge 70 relative to the cutters. By lightly holding the sections 71 and 72 on the guide a fast automatic feed of the hat to the cutters is assured. Immediately if the edge of the hat gets away from the cutters the operator can apply a slightly greater pressure to the hat over the guide 78 to slow up its travel or to fully stop its travel. This is a real advantage which cannot be accomplished with the usual automatic feed machines.

15 Although the hat 66 has been herein described as having angularly disposed portions 71 and 72, leading to the deformation 70, it will be understood that the general shape may be arcuate to various degrees (as shown in slight degree in Fig. 20 6). Also, the angle and spacing of the brim relative to the crown may vary greatly, and the apparatus of the present invention still function in a highly satisfactory manner without the use of a templet and substantially without alteration. 25 Other variations and modifications may be made within the scope of this invention and portions of the improvements may be used without others.

Having thus described the invention, what is 30 claimed as new is:

1. In a device of the character described, for trimming a hat, the combination of a rotary cutter; a pair of rollers, one of the pair of rollers being positioned on each side of said cutter, having angularly disposed peripheral faces defining an annular groove; a second cutter cooperable with said first named cutter; a roller associated with and positioned at one side of said second cutter, said second cutter and associated roller 40 having angularly disposed peripheral faces complementary to the angularly disposed peripheral faces of said pair of rollers and extending into the annular groove defined thereby to cooperate with said pair of rollers in guiding the hat relative to the cutters; and a guide extending toward said cutters and in line with said annular groove for partially supporting and for directing the hat to the cutters and rollers.

2. In a device of the character described, for 50 trimming a hat in which a crease has been formed defined by the line of meeting of portions angularly disposed relative to each other, the combination of a rotary cutter; two rollers, one of the two rollers being positioned at each side 55 of said cutter; oppositely bevelled peripheral faces on said rollers defining an annular groove; a second rotary cutter cooperable with said first named cutter; a roller positioned at one side of said second named cutter; and oppositely bevelled 60 peripheral faces on said second cutter and associated roller complementary to the oppositely bevelled peripheral faces of said first named rollers and extending into the annular groove defined thereby to cooperate with the peripheral faces of said first named rollers and with said angularly disposed portions of the hat for guiding the hat relative to the cutters.

3. In a device of the character described, for 70 trimming a hat in which a crease has been formed defined by the line of meeting of portions angularly disposed relative to each other, the combination of a rotary cutter; two rollers, one of the two rollers being positioned on each side of said cutter and movable 75 upwardly and downwardly relative thereto;

oppositely bevelled peripheral faces on said rollers defining an annular groove; a second rotary cutter cooperable with said first named cutter; a roller positioned at one side of said second named cutter; and oppositely bevelled peripheral faces on said second cutter and associated roller complementary to the oppositely bevelled peripheral faces of said first named rollers and extending into the annular groove defined thereby to cooperate with the peripheral faces of said first named rollers and with said angularly disposed portions of the hat for guiding the hat relative to the cutters.

4. In a device of the character described, for trimming a hat, the combination of an upper 15 shaft; a rotary cutter mounted on said shaft; a pair of rollers, one of the pair of rollers being positioned on each side of said cutter, carried by said upper shaft and movable transversely thereof; angularly disposed peripheral faces on said pair of rollers defining an annular groove; a lower shaft; a second rotary cutter mounted on said lower shaft and cooperable with said first named cutter; a roller associated with and carried by said lower shaft at 20 one side of said second cutter; and angularly disposed peripheral faces on said second cutter and associated roller complementary to the angularly disposed peripheral faces on said pair of rollers and extending into the annular groove 25 defined thereby to cooperate with said pair of rollers in guiding the hat relative to the cutters.

5. In a device of the character described, for trimming a hat, the combination of an upper shaft; a rotary cutter mounted on said shaft; a 35 pair of rollers, one of the pair of rollers being positioned on each side of said cutter, carried by said upper shaft and movable transversely thereof; angularly disposed peripheral faces on said pair of rollers defining an annular groove; a 40 lower shaft; a second rotary cutter mounted on said lower shaft and cooperable with said first named cutter; a roller associated with and carried by said lower shaft at one side of said second cutter; angularly disposed peripheral faces on 45 said second cutter and associated roller complementary to the angularly disposed peripheral faces on said pair of rollers and extending into the annular groove defined thereby to cooperate with said pair of rollers in guiding the material 50 relative to the cutter, and a stationary guide extending toward said cutter and in line with said groove for partially supporting and for directing the hat to the cutters and rollers.

6. In a device of the character described, for 55 trimming a hat in which a crease has been formed defined by the line of meeting of portions angularly disposed relative to each other, the combination of a pair of opposed cutters; driving means for said cutters; a pair of semi-floating 60 rollers, one of the pair of rollers being positioned on each side of one of said cutters, movable upwardly and downwardly relative thereto, and having angularly disposed peripheral faces defining an annular groove; and a stationary 65 guide for partially supporting and for directing material to the cutters and rollers, said stationary guide and said angularly disposed peripheral faces of the pair of semi-floating rollers constituting means engageable with said angularly disposed portions for automatically guiding and feeding the hat whereby the extent of feed may be controlled by the pressure of an operator's fingers.

7. In a device of the character described, for 75

trimming a hat, the combination of an upper shaft; a rotary cutter mounted on said shaft; a pair of semi-floating rollers, one of the pair of rollers being positioned on each side of said cutter, urged downwardly solely by their own weight; angularly disposed peripheral faces on said pair of rollers defining an annular groove; a lower shaft; a second rotary cutter mounted on said lower shaft and cooperable with said first named cutter; a roller positioned at one side of said second cutter; and angularly disposed peripheral faces on said second cutter and associated roller complementary to the angularly disposed peripheral faces on said first pair of rollers 15 and extending into the annular groove defined thereby to cooperate with said pair of rollers in guiding and feeding the hat relative to the cutters.

8. In a device of the character described, for trimming a hat in which a crease has been formed defined by the line of meeting of portions angularly disposed relative to each other, the combination of a trimming means; a rotatable means having diverging peripheral faces defining a peripheral groove for locating said trimming means and for receiving said angularly disposed portions, said trimming means being positioned at the center of said groove; and means providing converging faces complementary to the diverging peripheral faces and extending into said groove to cooperate directly therewith in guiding said hat relative to said trimming means.

9. In a device of the character described, for trimming a hat in which a crease has been formed defined by the line of meeting of portions angularly disposed relative to each other, the combination of a trimming means; a rotatable means having diverging peripheral faces defining a peripheral groove for locating said trimming means 40 and for receiving said angularly disposed portions, said trimming means being positioned at the center of said peripheral groove; and opposed rotatable means providing converging peripheral faces complementary to the diverging peripheral faces 45 and extending into the groove to cooperate directly therewith in guiding and feeding said hat relative to said trimming means.

10. In a device of the character described, for trimming a hat in which a crease has been formed defined by the line of meeting of portions angularly disposed relative to each other, the combination of a trimming means; rotatable means urged downwardly solely by its own weight and having diverging peripheral faces defining a peripheral groove for locating said trimming means and for receiving said angularly disposed portions, said rotatable means being movable upwardly and downwardly independently of said trimming means; and opposed rotatable means 55 providing converging peripheral faces complementary to the diverging peripheral faces and extending into the groove defined thereby to cooperate directly therewith in guiding and feeding said hat relative to said trimming means.

65 11. In a device of the character described, for trimming a hat in which a crease has been formed

defined by the line of meeting of portions angularly disposed relative to each other, the combination of a trimming means; a rotatable means defining a peripheral groove for locating said trimming means and for receiving said angularly disposed portions; opposed rotatable means providing converging peripheral faces extending into said groove to cooperate with said first named rotatable means in guiding and feeding said hat relative to said trimming means; and an arcuate guide, extending toward said trimming means and in line with said peripheral groove, having converging upper side walls cooperable with said angularly disposed portions for directing the hat to the trimming means and the peripheral groove. 15

12. In a device of the character described, for trimming a hat in which a crease has been formed defined by the line of meeting of portions angularly disposed relative to each other, the combination of a pair of opposed upper and lower cutting disks; and a pair of semi-floating rollers, one of the pair of rollers being positioned on each side of said upper disk, urged downwardly solely by their own weight, and engageable with said angularly disposed portions for guiding the hat 25 relative to the opposed cutting disks, said rollers being movable upwardly and downwardly independently of said upper disk.

13. In a device of the character described, for trimming a hat in which a crease has been formed defined by the line of meeting of portions angularly disposed relative to each other, the combination of a pair of shafts; a pair of opposed rotary cutters having material cutting portions 30 and respectively carried by said shafts; means carried by one of said shafts and movable transversely relative thereto, defining a groove for locating said material cutting portions and for receiving the angularly disposed portions of the hat; and means carried by the other of said 35 shafts providing converging faces extending into said groove to cooperate with said first named means in guiding and feeding the hat relative to the cutters.

14. In a device of the character described, for trimming a hat in which a crease has been formed defined by the line of meeting of portions angularly disposed relative to each other, the combination of a pair of shafts; a pair of opposed rotary cutters respectively carried by said shafts; 45 a pair of semi-floating rollers, one of said pair of rollers being positioned on each side of one of said cutters, having oppositely bevelled peripheral faces adapted to engage with said angularly disposed portions of the hat for guiding the latter relative to the cutters; rotatable means carried by the other of said shafts adapted to cooperate with said pair of rollers in guiding and feeding the material relative to the cutters; and an arcuate guide, extending toward said cutters 50 and in line therewith, having angularly disposed upper side walls adapted to direct the hat to the cutters and associated rollers. 55
